UNITED STATES PATENT OFFICE

IRVING K. PECK, OF CHICAGO, ILLINOIS, ASSIGNOR TO ASSOCIATED ENGINEERS COMPANY, OF CHICAGO, ILLINOIS, A CORPORATION OF ILLINOIS

GAS VENT

Application filed March 10, 1930. Serial No. 434,802.

My invention relates to a venting device for gas lines.

The three general means of transporting gas to customers are by means of so-called low, intermediate, and high pressure means or systems. Gas appliances in homes, etc., are generally designed to utilize gas at pressures of from four to eight inches of water, and the low pressure systems transport gas through the city streets, alleys, etc., connecting with the customers' services, meters, and house pipings at this pressure. In many cases, however, gas is delivered through the mains or systems at pressures higher than that for which the gas appliances are designed—say from fifteen inches of water to five or more pounds of pressure—and it is then necessary to install what is termed a house regulator, or governor, in the service line where it enters the house which is usually in the basement.

The purpose of this regulator is to reduce the main pressure to that for which the gas appliances are designed, namely to around four to eight inches of water. Where the high pressures are used, which may vary from fifteen to one hundred or more pounds per square inch, a regulator is used also as in the case just mentioned. In fact, a regulator is always used where the pressure of the gas supply is appreciably higher than the pressure used by the appliances.

In order to safeguard the customers, should a regulator fail to operate properly, from having these high pressures in the pipings, meters, and appliances, thereby creating a hazard, the regulator is generally vented by means of a self contained mercury or dead weight seal and a pipe leading to the outdoors. Obviously, it is necessary that this line and outdoor opening be kept unobstructed to guarantee the proper venting of any gases. The common practice has been to run a so-called pipe nipple or a short length of pipe through the building wall approximately eighteen inches above the ground level and to leave this piece of pipe open to the atmosphere or to connect an ordinary pipe elbow, etc., to the end of it to direct the opening down so as to prevent rain, snow, etc. from entering and blocking the opening. Such

small round openings lend themselves to being easily plugged by anyone with a piece of rag, sticks, or small stones, and insects often build their nests inside and across this opening which results in its becoming clogged.

The principal purpose of this invention is to provide a one piece unit which may be installed on the end of the pipe projecting through the wall, which unit is so constructed as to make it practically impossible to completely plug the vent or have it freeze over in the winter.

More particularly the purpose of this invention is to provide a vent of this nature having a down-turned outlet that is webbed and recessed to eliminate plugging, and also has an additional opening so close to the building wall as to practically prevent physical plugging.

Other objects and advantages of the invention will appear as the description proceeds in connection with the accompanying drawings wherein the preferred form of the invention is shown. It is to be understood, however, that the disclosure is illustrative only and is not to be taken as limiting the invention except in so far as it is limited by the claims.

In the drawings—

Fig. 1 is a more or less diagrammatic view showing the usual gas installation where regulation and vent are required, and the position of the venting device which forms the subject matter of this invention;

Fig. 2 is a vertical section through the vent and the pipe to which it is attached;

Fig. 3 is a rear end view of the vent;

Fig. 4 is a bottom view of the vent;

Fig. 5 is a view similar to Fig. 3 of a slightly modified form of vent; and

Fig. 6 is a vertical section through the vent shown in Fig. 5.

Referring now in detail to the drawings, the usual intermediate or high pressure gas installation will consist of the inlet conduit 10 which enters the basement under ground and passes upwardly through the regulator 11 to the meter 12 from which the distributing pipe 13 runs to the various appliances. The regulator 11, of course, serves—as hereinbefore

referred to—to reduce the pressure down to such a value as is required by the appliances. The structure just described is common and well known and forms no part of the present invention.

5. The regulator 11, however, is vented by means of the upwardly extending pipe 14 having the horizontal nipple 15 extending through the wall of the building to the exterior thereof a short distance above the ground. The outer end of this pipe 15 has my improved vent element 16 thereon.

This element 16 is preferably in the form of a one piece casting or forging having an 15 interiorly screw-threaded neck 17 to fit over the end of the pipe 15, and preferably the element 16 is screwed on sufficiently to make it fit rather tightly up against the wall of the building. The casting 16 then has a depending portion 18 which as shown is substantially rectangular in cross section and has an opening downward at 19 which opening is divided by the webs 20 and 21 into a plurality of smaller outlets. The opening is also preferably recessed as indicated at 22 so as to prevent water which falls on the exterior from reaching the webs 20 and 21 and to further aid in preventing plugging of the outlet.

In addition, the depending extension 18 30 has on the face thereof which is directed toward the wall an additional vent opening 23. This opening is preferably directed somewhat downwardly so as to drain readily and prevent water from getting inside the hollow 35 casting 16. Its position with respect to the building wall is such as to make it practically impossible for it to become clogged by the insertion of any material, and the position of the two openings 19 and 23 are as 40 will be seen such that there is very little likelihood of both of them being plugged at the same time. Moreover, owing to the fact that they are directed in different directions, air circulation through them is encouraged 45 which will tend to prevent insects such as spiders and the like from building nests that would plug them.

In Figs. 5 and 6 a slightly different form of vent casting is used. This casting consists 50 of the ring 24 which is connected by a series of webs such as 25 and 26 to an exterior cap 27 which cap completely surrounds the ring 24 but is offset laterally with respect thereto 55 so that the ring 24 may be screwed up against the building and still leave a slight space between the cap and the building wall which space would be rather hard to plug, particularly in view of the fact that the openings between the webs such as 25 and 26 are spaced 60 entirely around the ring 24 and an effective plugging could only be accomplished by something which encircles the plug 24 between the cap 27 and the wall.

While this form does not have the advantages of the form illustrated in Figs. 2 to 4,

it nevertheless has certain advantages in that it cannot be turned wrong side up and left facing upwardly accidentally. It is, however, more subject to being clogged by rain or freezing, and the form in Fig. 2 to 4 is 70 considered the preferred form.

Having thus described my invention, what I claim as new and desire to secure by Letters Patent is:

1. A vent cap for gas systems comprising a one piece casing having a screw threaded portion to receive an outlet pipe and having a plurality of outlet openings at least one of which is directed in the same general direction as the screw threaded portion, some 80 of said openings being at different level than others.

2. A vent cap for gas vent pipes comprising a one piece hollow casing having a lateral opening screw threaded to receive the 85 pipe and having a depending rectangular portion provided with outlet openings in the lower end and a lateral outlet opening beneath the first named lateral opening.

In witness whereof, I hereunto subscribe my name this 21st day of February, A. D. 1930.

IRVING K. PECK.
